UNITED STATES PATENT OFFICE

ROBERTO KURTZ, OF BUENOS AIRES, ARGENTINA

EXCAVATING MACHINE

Application filed May 19, 1924. Serial No. 714,197.

This invention relates to an improved type of excavating machine, particularly adapted for the grading of roads.

The improved machine comprises essentially a main body having supporting wheels, the relative levels of which may be adjusted according to the excavation being made, a transverse rigid supporting beam pivotally mounted at one end thereof on the main body and having its other end adjustable upwardly and downwardly about its pivot, and excavating means movably supported and guided upon and by said beam and comprising drag chains and excavating buckets by means of which the dirt, gravel or the like material of the road or other surface is excavated.

The machine is preferably provided with its own motor for effecting operation of the different means thereon and for transportation of the machine.

Hereinafter for convenience a separate description is given of the five essential parts of the machine viz: the suspension system; the rigid movable supporting beam; the excavating or drag means; the motion transmission means; and the stabilizer.

One form of machine is illustrated in the accompanying drawings in which Figure 1 is a rear elevation of the machine in working position; Fig. 2 is a plan view with the excavating means removed; Fig. 3 is a side elevation with the excavating means removed; and Figs. 4, 5 and 6 are detail views of certain parts as will be described.

Suspension system

The main body of the machine is formed of a horizontal platform A, Figs. 1, 2, 3, which may be of cast iron, and has two vertical depending plates, one in the front, and one in the rear, marked A¹ and A² respectively, Fig. 3.

This main body is supported at the front part thereof on a single supporting and steering wheel W¹, Fig. 3, which is rotatably mounted in two bearing brackets, b, secured to a circular plate f rotatably carried by the column c. This column is composed of two spaced channel bars c¹ which may be of wrought iron and which embrace and are

guided by two grooved brackets d, d¹, attached to the vertical plate A¹ of the main body. Between the two bars c¹, a screw threaded spindle is arranged, which is threaded into the bracket d, and is adapted to be rotated by the hand wheel e, and thus serves to raise or lower the column and the wheel W¹ in relation to the main body.

The circular plate f is adapted to be turned about a central pivot on the column c, and with it the brackets b and the wheel W¹. This circular plate is provided with teeth f¹ adapted to mesh with a pinion f², secured to the lower end of a spindle g rotatable in the brackets g¹ on the column c and having the hand wheel g². The angular position of the wheel W¹ in regard to the main body of the machine can thus be changed at will, so as to determine the direction in which the machine advances.

The main body is supported at its rear part upon two supporting wheels W² W³, mounted upon a rear axle C, enclosed within a rear axle housing D, Fig. 1.

The connection between this housing D and the main body is obtained by a special pivotal arrangement shown in detail in Fig. 6, which permits alteration in a vertical plane of the angular position of the axle with regard to the main body, and at the same time permits the transmission of motion to the axle in any such angular position.

Two arms D¹ of the casing D, Figs. 1 and 6, embrace the plate A² of the main body, and are traversed by a hollow pivot E, through the aperture of which extends a spindle E¹, which transmits motion, by means of a set of bevel pinions E² to the worm E³ which meshes with the worm wheel E⁴, secured to the axle C.

It will be readily seen that by such arrangement motion is always properly transmitted to the axle whatever the angular position of the housing and axle may be in regard to the main body.

The position of the axle and housing is determined by means of an arrangement similar to that employed for adjusting the front wheel, which has already been described. The two channel bars F, constituting the col-

umn, embrace and are guided by grooves in the vertical plate A^2 of the main body and at their lower ends they carry a roller F^1 , shown in dotted lines in Fig. 1, which rests upon the 5 axle housing D. The hand wheel F^2 at the upper end of the column is secured to a threaded spindle F^3 , threaded into the platform A so that by turning the wheel F^2 , the relative positions of the platform and housing may be varied by relative movement about the pivot E. The roller F^1 permits the necessary sliding movement of the housing D relatively to the column F during such adjustment.

15 By the arrangements described, the whole machine is supported upon the three wheels, W^1 , W^2 , W^3 , the front one W^1 rolling on the natural ground, and the two rear ones rolling on the bottom of the finished excavation, 20 and the relative levels of the three wheels can be modified at will, while the platform A is maintained in a substantially horizontal position, and the motion is properly transmitted to the rear axle. It will be understood that the rear axle may be divided and 25 driven through a differential mechanism, if desired.

Rigid beam

30 The rigid beam is composed of two spaced apart, symmetrical plates K, K^1 , which may be of cast iron united by transverse braces l , l^1 . The shape of these plates, in cross section, is shown in detail in Fig. 5.

35 Extending around the entire peripheral edge of each plate, and on the inside face of the plate is formed a guide groove or channel K^2 which serves for the guidance and support of the wheels of the excavating or drag elements hereinafter mentioned.

40 The lower edge of each plate K, K^1 , of the rigid beam corresponds in contour to the transversal contour of the excavation for which the machine is designed.

45 At the right hand end thereof, the rigid beam comprising the plates, K, K^1 , is pivotally mounted on the shaft k which is carried by the two brackets H, H^1 , suitably secured to the depending plates A^1 , A^2 of the main body. The shaft k is freely rotatable in the 50 bearings at the ends of the plates K, K^1 and also in the bearings of the two brackets H, H^1 .

At the left hand end thereof, the rigid beam is supported so that it may be adjusted 55 vertically, by means of two screw threaded spindles L, L^1 , Fig. 3, of opposite hand, the upper ends of which are connected by bevel pinions L^2 , L^3 , with a shaft T^1 hereinafter referred to. The spindles L, L^1 are supported 60 at their upper ends by the platform A and at their lower ends by brackets L^4 carried by the plates A^1 and A^2 , and they have threaded engagement with nuts m , m^1 carried by the plates K, K^1 of the rigid beam. The 65 nuts are mounted on the plates so as to be

capable of a slight sliding and angular movement, to permit the necessary pivotal movement of the beam about the shaft k , this detail of construction not being shown on the drawings.

At the left hand end of the rigid beam are arranged upper and lower shafts k^1 , k^2 , Fig. 2, which are arranged to rotate freely within the bearings of the plates K, K^1 , the three shafts k , k^1 and k^2 having secured thereto the sprocket wheels k^4 which are preferably arranged on the outside of the plates, as shown in Fig. 2, and which serve to drive the drag chains of the drag or excavating means.

The excavating or drag means

The excavating means is composed of a plurality of excavating elements, shown on an enlarged scale in Fig. 4. Each of these elements comprises a bucket or scoop P which is supported by means of four wheels P^1 mounted on two axles P^2 , carried by two brackets n , n^1 , secured to the buckets or scoops, Figs. 4 and 5, which wheels are so arranged as to travel within the grooves or channels K^2 of the plates K, K^1 of the rigid beam before referred to, whereby the buckets are positively supported and guided by the beam to move in the desired path during the excavating operation.

The buckets or scoops P are preferably bottomless and each of them is provided at the lower front part thereof with a knife p, or a plurality of knives or digging devices, the purpose of which is to plough up and loosen the soil in advance of the bucket.

The buckets or scoops P are connected to and moved by the two drag or drive chains P³ which travel over the sprockets k^4 mounted upon the shafts k , k^1 and k^2 of the rigid beam, these chains being provided with special links q by means of which connection is made with the buckets.

Motion transmission means

Power is furnished to drive the several mechanisms described, by a suitable electric or other motor M suitably mounted upon the platform A. The shaft M^1 of this motor is connected, through a suitable clutch (not shown) to drive a sprocket R which is connected by a sprocket chain R' with a sprocket R² mounted upon the shaft E¹ of the rear axle driving mechanism, before referred to, whereby the wheels W^2 , W^3 may be driven when desired to effect the movement or transport of the whole machine.

By means of another ordinary clutch (not shown) the motor shaft M^1 may be connected to drive a sprocket R³ connected by a sprocket chain R⁴ to a sprocket R⁵ secured to the shaft k , whereby the sprockets k^4 on this shaft may be driven, when desired, to effect the movement of the drag chains P³.

carrying the buckets P to effect the excavating operation.

The motor shaft M¹ also constantly drives, by means of pinions M² a secondary shaft T, in the opposite direction to the shaft M¹. Each of the shafts M¹ and T have secured thereto sprockets r which drive by means of sprocket chains r¹ two sprockets r² loosely mounted upon the shaft T¹, hereinbefore referred to, the sprockets r² rotating in opposite directions. By means of a suitable clutch S, Fig. 2, the shaft T¹ may be connected with one or the other of the sprockets, or may be disconnected from both of them. The shaft T¹ has secured thereto the bevel gears L³ before referred to, and by connecting the shaft T¹ with one or other of the sprockets r², the screw threaded spindles L, L¹ may be driven in one direction or the other whereby the rigid beam K, K¹ may be raised or lowered at the left hand end thereof, about the shaft k, in order to vary the plane of operation of the buckets P and the depth of the excavating operation.

25

The stabilizer

In order to avoid the machine slipping towards the bottom of the ditch or excavation, as the natural tendency would be, a stabilizer is provided. On the bracket Z, attached to the plate A² of the main body, is mounted a column V of the same kind as the columns F and C already described. This column supports at its lower end, by means of brackets V¹, V² secured to the channel bars constituting the column, a series of rollers V³ which are adapted to coat with the inclined face V⁴ of the excavation and thereby to maintain the machine, during its forward movement, in the proper line of travel. By means of the hand wheel v, which operates a threaded spindle co-acting with the bracket Z, the column and thereby the series of rollers may be raised or lowered at will.

Operation

When the wheels W² and W³ are maintained at the same level (in regard to the main body) as the wheel W¹, the machine is ready for transport by the action of its own motor and can be transported to the place where the ditching or excavating is to be carried on.

Having arrived at the place to be excavated, the wheels W¹ and W³ are adjusted relatively to the main body, and while the machine is stationary the drag chains and the excavating buckets are put into operation by clutching the sprocket R³ to the motor shaft, and excavation starts. By clutching the shaft T¹ to one or other of the sprockets r², the left hand end of the rigid beam K, K¹ is lowered to a certain depth while the drag chains and buckets are in operation, and then raised

again. The machine has now made an excavation on an inclined plane, and the drag chains are thrown out of operation, and the sprocket R is clutched to the motor shaft, so that the machine advances a length equal to the width of the rigid beam. Wheels W¹ and W³ and the body are then relatively adjusted a little more and the operation repeated till the desired depth of excavation is obtained. From now on the platform A of the main body is always maintained in a horizontal position due to the relative adjustment of the supporting wheels. The machine is so adjusted that in such a position of the main body the shaft k is in the proper position to obtain the desired grading. The left hand end of the rigid beam K, K¹ goes up and down to the necessary depth while the drag chains and buckets are in operation, for which purpose proper indicators (not shown on the plans) may be provided. Each time the excavating buckets reach the limit depth, the rigid beam is raised, and the machine advances a length equal to the width of the beam or excavation.

The earth removed by the knives p (Fig. 4) of the excavating buckets is pushed by the bottomless buckets P up to the end of the rigid beam, from which point it may be removed, or may be spread by any suitable means.

It is to be understood that while a specific embodiment of the invention has been described in detail, the invention is not limited to the particular devices and constructions described for effecting the desired operations or adjustments as the same may be variously changed or modified as may be desired, the scope of the invention being defined by the claims appended hereto.

Having thus described my invention what I claim and desire to secure by Letters Patent is:

1. An excavating machine comprising a main body, wheels for supporting the same, an adjustable excavating unit carried by the body, and a rear axle, on which a pair of such wheels is mounted, equipped with driving mechanism therefor, enclosed within a casing joined to the main body by means of a hollow pivot.

2. An excavating machine, comprising a main body, an excavating unit operable transversely of said body, means for adjusting said excavating unit vertically relatively to said body to determine the depth of the excavation and the inclination of the excavated surface, front and rear supporting wheels carried by said body, and means for adjusting said supporting wheels to permit the former to travel on the natural ground and the latter to travel on the inclined excavated surface while maintaining said body in a substantially horizontal position.

3. An excavating machine, comprising a

main body, a rigid beam extending transversely of said body and pivotally supported at one end thereof by said body, adjustable means between said body and said beam for effecting vertical adjustment of said beam about its pivotal support to vary the depth of the excavation and the inclination of the excavated surface, excavating means carried by said beam and movable thereon transversely of said body, front and rear supporting wheels mounted on said body, and means for adjusting said rear supporting wheels to cause the same to travel on the inclined excavated surface while maintaining said body in a substantially horizontal position.

4. An excavating machine, comprising a main body, a driven excavating means mounted on said body transversely thereof and adapted to travel transversely of said body to effect excavation of material, means for effecting vertical adjustment of said excavating means relatively to said body to vary the depth of the excavation and the inclination of the excavated surface, front and rear supporting wheels carried by said body, and means for adjusting the rear supporting wheels and axle thereof as a unit relatively to said main body to permit said wheels to travel on the inclined excavated surface while maintaining said body substantially horizontal.

5. An excavating machine, comprising a main body, front and rear supporting wheels carried by said body, an excavating unit suspended beneath said body between said front and rear supporting wheels and including excavating elements travelling in a predetermined path in a plane at right angles to the direction of movement of said body, means for vertically adjusting said excavating unit relatively to said body to vary the depth of the excavation and to hold said excavating unit positively in adjusted position, and means for effecting relative adjustment between both the front and the rear supporting wheels and the body to permit the front wheel to travel on the natural ground and the rear wheels to travel on the excavated surface while maintaining the body in a substantially horizontal position.

6. An excavating machine, comprising a main body, a front supporting wheel, rear supporting wheels, an adjustable excavating unit carried by said body and operative while the machine is stationary and including excavating elements travelling in a predetermined path in a plane at right angles to the direction of movement of said body in a direction transverse to said body, means for vertically adjusting said excavating unit relatively to said body to vary the depth or inclination of the excavated surface and to hold said excavating unit positively in adjusted position, and means for raising and

lowering the front wheel relatively to the main body.

7. An excavating machine, comprising a main body, a front supporting wheel and rear supporting wheels carried by said body, an excavating unit carried by said body and operative while the machine is stationary in a direction transverse to said body, means for vertically adjusting said excavating unit to vary the depth of the excavation and the inclination of the excavated surface, means for raising and lowering the front wheel relatively to the main body, and means for adjusting the rear wheels relatively to said body to permit the same to travel on the excavated surface while maintaining said body in a substantially horizontal position.

8. An excavating machine, comprising a main body, front and rear supporting wheels therefor, an excavating unit carried by said body and extending transversely thereof, means for effecting vertical adjustment of said excavating unit relatively to said body to vary the depth of the excavation and the inclination of the excavated surface, said rear supporting wheels and the driving axle therefor, being carried by a support pivotally connected to said body about a longitudinal axis, means for driving said axle in all positions of said support, and means for effecting pivotal movement of said support about said axis relatively to said body to permit the rear wheels to travel on the inclined excavated surface while maintaining the body in a substantially horizontal position.

9. An excavating machine, comprising a main body, front and rear supporting wheels therefor, an excavating unit carried by said body and extending transversely thereof, means for effecting vertical adjustment of said excavating unit relatively to said body to vary the depth of the excavation and the inclination of the excavated surface, said rear supporting wheels and the axle therefor comprising a unit pivotally connected to said body about a longitudinal axis, means for effecting pivotal movement of said wheel unit about said axis relatively to said body to permit the rear wheels to travel on the inclined excavated surface while maintaining the body in a substantially horizontal position, and driving means on said body for driving said rear wheels, including an element rotatable about an axis coincident with the pivotal axis of the wheel unit.

10. An excavating machine, comprising a main body, a front wheel and rear supporting wheels carried by said body, a rigid beam extending transversely of said body and suspended therefrom between said front and rear supporting wheels, the contour of the lower edge of said beam corresponding to the shape of the transverse contour of the excavation to be made, excavating elements

guided in their travel by the lower edge of said beam, and means for positioning said rear wheels relatively to said body to travel on the excavated surface while maintaining said body in a substantially horizontal position.

11. An excavating machine, comprising a main body, comprising a front wheel and rear supporting wheels, a rigid beam carried by said body transversely thereof between said front and rear supporting wheels and provided at least at its lower peripheral edge with a guide groove or channel corresponding to the shape of the transverse contour of the excavation to be made, a series of movable excavating elements having supporting wheels movable within said channel, and means for positioning said rear supporting wheels relatively to the body to travel on the surface excavated by said elements while maintaining the body in a substantially horizontal position.

12. An excavating machine composed of a main body, means for supporting the same, a rigid beam mounted on said body, and drag chains supported on said beam for movement in a closed path and carrying excavating elements, each one of the latter comprising an open bottomed scoop operative to push the earth up to the end of the rigid beam and leave it there, and means at the front of said scoop for ploughing and loosening the earth.

13. An excavating machine including a main body, an excavating unit carried thereby and operable in a direction transverse to the direction of movement of said body to form a main upwardly inclined excavated surface and an outwardly and upwardly inclined lateral face at the outer side of said surface, and a stabilizer mounted on said body and provided with a pressure element inclined correspondingly to said lateral face and adapted to engage therewith throughout its length.

14. An excavating machine including a main body, an excavating unit carried thereby and operable in a direction transverse to the direction of movement of said body to form a main upwardly inclined excavated surface and an upwardly and outwardly inclined lateral face at the outer side of said surface, and a stabilizer mounted on said body and having a pressure element comprising a series of rollers having their axes inclined correspondingly to said lateral face and adapted to engage said face throughout their lengths and to roll therewith.

In testimony whereof I affix my signature.

ROBERTO KURTZ.
